UNITED STATES PATENT OFFICE.

INGEMAR K. RYSTEDT, OF DAYTON, OHIO, ASSIGNOR OF ONE-FOURTH TO GEORGE K. ANDER AND ONE-FOURTH TO A. H. DUNHAM.

DEPOSITORY ADVERTISING CABINET OR THE LIKE.

Application filed March 27, 1925, Serial No. 18,735. Renewed January 12, 1927.

This invention relates to depository-advertising cabinets having particular reference to a structure which is suitable in design and utility features to be located in a 5 public place, as on the public sidewalk in a city.

The object attained in my invention is a depository for refuse, concealed in an ornamental cabinet which serves the further purpose of an advertising medium and for displaying street signs, etc., the means for displaying advertisements being movable preferably to render the advertisements more effective.

To this end, a cabinet of artistic design, preferably made of metal, is provided to give attractiveness of appearance to the structure as a whole. Concealed in the cabinet is a receptacle for refuse with a drop-lid opening 10 in the cabinet arranged relative thereto. Within the cabinet also, in a preferred form of my invention, is a movable (rotatable as here shown) advertising medium, operable through alternate steps and movements to 15 display advertisements progressively on the different sides or faces of the cabinet,—the cabinet as here shown being generally rectangular shaped and having open glass panels on all sides through which the advertisements are displayed. In the form herein shown, the top of the cabinet is provided 20 with a rectangular shaped housing upon the four faces of which the names of intersecting streets may be indicated.

In the accompanying drawings:

Fig. 1 is an elevation of the cabinet;

Fig. 2 is a vertical sectional view;

Fig. 3 is an elevation of the advertising unit removed from the cabinet;

Fig. 4 is a detail view of a hinged panel;

Fig. 5 is a plan view of the spring motor;

Fig. 6 is a cross-sectional view taken on line 6—6 of Fig. 1;

Fig. 7 is a sectional view taken on line 45 7—7 of Fig. 6.

The cabinet, as here shown, consists of a main structure 1 which serves as a housing for the advertising mechanism and the refuse receptacle, the portion 2 at the top 50 serving as a medium for displaying street signs and small fixed advertisements. The housing 1 is octagonal-shaped, is supported on a base 3, has a front or door panel 4, three main side panels 5 and four intermediate

panels 6, all the panels as here shown being 55 glass, the structure being covered with a metal top 7, electric lights 8 located advantageously serving to light the interior of the structure.

The glass is retained in the panels by 60 means of U-shaped flexible bindings 9 made of any suitable material, as rubber, secured by means of metal clips 10, which serve the double purpose of holding the glass firmly in position and also act as buffers to prevent 65 rattling and minimize the possibilities of breaking the glass.

Supported within the cabinet is a rectangular-shaped structure 11, closed on all sides and bottom and open at the top, the structure being supported rotatably on a vertical axle 12 having bearings in upper and lower base frames 13 and 14 which are secured in any suitable manner to the outer cabinet. The axle 12 is preferably provided with a 70 roller sleeve bearing 15 in frame member 13 and a single roller ball-bearing 16 in a bearing extension member 17 secured to the under side of frame 14.

The front panel 11^a of the structure 11 is 75 hinged in any suitable manner to permit the panel to swing open outwardly, when the cabinet door 4 is open, to afford access to the interior of the structure to remove and replace therein a rectangular-shaped depository 18 which is also closed at the bottom, and open at the top to receive the refuse from a drop door 4^a in the outer cabinet, an annular-shaped apron 19 suspended inside the cabinet and having its lower portion extended into the top of the refuse receptacle, 80 acting as a guide for the refuse and as a guard to prevent portions thereof falling outside the receptacle. The receptacle 18 is supported free on the bottom of structure 11 85 and is supported against lateral displacement therein by a series of resilient buffers 20 secured inside on panels 11. A handle 21 is provided on the receptacle adjacent the panel 11^a for convenience in handling the 90 same to remove the refuse deposited therein.

The construction and arrangement of the inner member 11 relative to the structure as a whole, as here shown, is to provide a suitable medium for displaying advertisements 105 through the glass panels of the outer cabinet 1, the inner member being made rotatable to effect a sequence in the display of the ad-

vertisements, thus to add materially to the effectiveness of the cabinet as an advertising medium.

Any suitable mechanism, as an electric or mechanical motor, may be employed for operating the advertising unit of the cabinet. As here shown, a mechanical motor—spring motor—is employed for operating the rotatable member 11. The mechanism 10 consists of a spring motor 22 adapted to be wound by a crank 23, through suitable connections between the crank and motor, as bevel gears 24 and spur gears 25, these features in one form or another being common 15 to mechanical motors of this character. The motor is connected to the axle 12 of the unit 11 by means of spur gears 26—27, the latter gear being supported rotatably free on axle 12 and adapted to be rendered operative 20 with the shaft by means of a clutch 28 splined slidably on the axle.

To effect a step-by-step rotation of the advertising unit, a clock mechanism 29 is provided, as here shown, the same including 25 a 4-point escapement 30 secured to the hour shaft of the clock and associated by means of a lever 31 with four stops 32 on the spring motor gear 26, the relation of the parts one with the other being such that the gear 30 will be released for a quarter turn upon each quarter turn of the escapement 30, thus the advertising unit 11 will also be rotated a quarter turn upon each action of the escapement, which, as here shown, will be every 35 fifteen minutes. Thus each advertisement will be displayed progressively in repeated sequence through the four panels of the cabinet with stop intervals of fifteen minutes in each position.

40 Means are provided for interrupting operation of the advertising unit at all times when the cabinet door 4 is open, as when the advertisements are to be changed or the refuse receptacle is to be emptied, the means consisting, as here shown, of a pivoted lever 33 for shifting clutch 28, the shift lever being controlled by a spring tensioned push rod 34 which engages the heel of lever 33 as at 45 35 and acts when the lever is pressed inward by the action of cabinet door 4 thereon to hold the clutch in operative relation with gear 27. When the door is opened, a spring 36 acts to move rod 34 in the opposite direction thus permitting lever 33 to be drawn 50 in the opposite direction by a spring 37 which acts to throw out the clutch and to interrupt the driving relation between the spring motor and advertising unit 11 which will then be free to be rotated at will independently of its operating mechanism.

55 Any suitable means may be provided for winding the clock mechanism. As here shown, friction gears 38—39 associated with the crank shaft 23, a shaft 40 and bevel gears 41, are employed for winding the

clock, the friction gears adapting the clock-winding movement to the motor-winding movement irrespective of gear ratios.

Any suitable means, as the spring-tensioned devices 42, may be employed for holding the advertising posters on the panels of the rotatable structure 11, the device, as here shown, consisting of a spring-tensioned hinge 42—43 and a strip 45 operable on the hinges, a rubber element 44 being interposed 75 preferably between the pressure strips and the poster to obtain better contact.

The advertising unit is preferably provided with a bell 46 located at any convenient point as on the base plate 13, and having a striker 47 adapted to be actuated upon each quarter turn of the unit by projections 48 secured in the head of axle 12, thus upon each movement of the unit to effect a change 80 of position of the advertisements the bell 85 will be actuated to attract attention to the advertisements.

Having described my invention, I claim:

1. A depository for refuse including in combination with a stationary cabinet having open glass panels including a hinged panel, a structure supported rotatably in said cabinet including a hinged panel having means to support and display posters, as advertisements, through said stationary panels, a receptacle for refuse supported within said inner structure and removable upon opening of the hinged panels, and means, as a motor, for rotating the inner structure.

2. A depository for refuse including in combination with a stationary cabinet having open glass panels including an opening panel, a structure supported rotatably in said cabinet including an opening panel having means thereon to support and display posters, as advertisements, through said stationary panels, a receptacle for refuse supported within said inner structure and removable upon opening of the hinged panels, and means as a clock-controlled motor, for imparting a timed rotatable movement to said inner structure whereby to effect progressive intermittent alignment of the inner panel with the stationary panels for displaying said advertisements through the stationary panels, and means for interrupting said movement when said panels are opened.

3. A depository for refuse including in combination with a stationary cabinet having open glass panels, a structure supported rotatably in said cabinet and having means thereon to support and display posters, as advertisements, through said panels, a receptacle for refuse supported within and rotatable with said inner structure, and means, as a motor, for operating the inner structure.

4. A depository for refuse including in

- combination with a stationary cabinet having a plurality of panels and a door, a structure supported rotatably in said cabinet and having means thereon to support and display posters, as advertisements, through said panels, and a receptacle for refuse supported within said inner structure, and adapted to be removed from the cabinet through said door.
- 5 5. A depository for refuse including in combination with a stationary cabinet having a plurality of panels and a door constituting one of said panels, a structure supported rotatably in said cabinet having a corresponding plurality of panels and a door constituting one of said panels, all of the panels of the inner structure being adapted to support posters, as advertisements, and to be moved into alignment with said outer
- 10 20 panels whereby to display said advertise-
- ments therethrough, and a receptacle for refuse supported within the inner structure and adapted to be removed through said doors.
6. A depository for refuse including in combination with a stationary cabinet having a plurality of panels and a door, a structure supported rotatably in said cabinet and having means thereon to support and display posters, as advertisements, through said panels, a receptacle for refuse supported within said inner structure and adapted to be removed from the cabinet through said door, means as a motor, for rotating the inner member, and means operatively associated with said door for controlling the operating relation between the motor and said member.

In testimony whereof I affix my signature.

INGEMAR K. RYSTEDT.
